UNITED STATES PATENT OFFICE

CHARLES SPIRO, OF NEW YORK, N. Y.

STEAM ENGINE

Application filed November 1, 1926. Serial No. 145,516.

This invention relates to a steam engine and particularly to a construction wherein the propelling vapor is generated directly within a heated cylinder and to such extent as to develop the power desired.

In this type of engine a material difficulty in practical operation has arisen by the introduction of a large body of liquid at a low temperature which required such a period 10 to vaporize within the heated cylinder that the movement of the engine piston was reduced in speed to a point where effective results could not be secured. Further the heat units carried by the fluid exhausted from 15 the cylinder at each stroke of the piston were lost and accomplished no further work.

To overcome such objections I have provided means by which the liquid may be successively fed in small quantities and at a 20 high temperature so that its vaporization is effected substantially immediately upon entering the heated cylinder and the pressure built up to effect the desired speed and power in operation. This results in a new method 25 of operation by which the liquid is first vaporized to actuate the piston, then condensed after being exhausted from the cylinder, and subsequently the condensate is refed to the cylinder for revaporization. Such method 30 conserves many of the heat units originally transmitted to the liquid in the vaporization step and assists in maintaining the temperature of the cylinder by feeding a heated liquid thereto.

35 The invention has for an object to provide a novel and improved method of operating an engine of the cylinder and piston type consisting in alternately introducing into the opposite ends of a heated cylinder a 40 liquid to be thereby vaporized, exhausting the resultant vapor at the end of each stroke, condensing such vapor, and refeeding the heated condensate to the cylinder for further vaporization.

45 A further object of the invention is to present a new construction of engine including a heated cylinder and piston therein, with alternately actuated means for feeding liquid at each end of the cylinder and exhausting vapor therefrom, and means for

condensating the exhausted vapor and refeeding it to the cylinder as a heated liquid.

Another object of the invention is to provide an improved feeding means for a vapor generating cylinder in which the piston has its rod extended in opposite directions and provided with means for successively feeding limited quantities of liquid to the cylinder. 55

The invention also has for an object to present a novel structure in which the cylinder is enclosed within a heating chamber and formed with heads having exhaust valves connected for intermittent opening and closing movement controlled by the opposite movements of the rod from the piston within 60 the cylinder, together with liquid intake ports in the heads automatically controlled by such movements of the rod to alternately feed at opposite sides of the piston. 65

Other and further objects and advantages 70 of the invention will be hereinafter set forth and the novel features thereof defined by the appended claims.

In the drawings—

Figure 1 is a vertical longitudinal section 75 of the invention;

Figure 2 is a detail section at one end of the cylinder, and

Figure 3 is a fragmentary detail, with the piston rod broken away to show the valve 80 operating connections.

Like numerals refer to like parts in the several figures of the drawings.

The invention is adapted for various applications and while described as a steam engine, other liquid may be vaporized therein and used for its propulsion. In the embodiment of the invention herein shown the cylinder 10 is provided with heads 11 at its opposite ends each having an intake 12 for liquid 85 and an exhaust 13 for steam. The exhaust ports are controlled by suitable valves, such as for instance as the cocks 14 having a cut-away passage therethrough, and each valve carries an operating lever 15. The opposite levers 90 are connected for joint operation by a link 16, so that when one exhaust valve is opened the other is closed.

Within the cylinder a working piston 17 95 is disposed and the rod 18 therefrom extends 100

in opposite directions and is suitably packed where passing through the heads 11. One end of the rod 18 is connected to a sliding cross head 19 from which a pitman 20 extends to the crank shaft of a fly-wheel 21 to provide momentum to carry the piston over the points of no power at the ends of the strokes. The rod is also provided with laterally projected pushers 22 which at the opposite extremes of travel engage the levers 15 from the exhaust valves to effect an automatic shifting thereof.

For the purpose of feeding a liquid into the heated cylinder to be vaporized thereby, different devices may be employed, but a preferred construction involves the formation of a series of separated grooves 23 in the rod 18 spaced from each face of the piston so as to register with the liquid intake port 12 at the end of the piston stroke in each direction. They thus receive a proper charge of liquid which is successively delivered in small quantities to the heated cylinder to effect a rapid vaporization and graduated increase of the power generated at the piston head therein.

Any desired means may be employed for heating the cylinder, for instance, a spaced drum 33 heated by burners 24 and having vents 25 to permit expansion of the heated air within the drum. This provides means for an even heating of the entire surface of the cylinder so that its full area is effective in vaporizing the liquid introduced.

In carrying out the method of operation present in this invention it is important to gradually feed the liquid at the highest possible temperature to flow into the cylinder heated to the point of vaporization, and for this purpose an elevated closed feed tank 26 is provided and communicates by pipes 27 with the intakes 12 which at proper intervals register with the piston rod grooves. From the exhaust ports 13 pipes 28 extend to a point above the water level in the tank so that the exhaust steam emitted therefrom engages the cooler upper portion of the tank and is thereby condensed. In order to prevent any back pressure from the tank acting upon the piston and maintain a lower pressure in the tank than present in the cylinder, the tank is open to atmosphere through a condensing coil 29 disposed in a chamber 30 through which a cooling agent may be passed by the pipes 31.

In the operation of the engine with the parts in the position shown in Figure 1, the liquid feed at the right is cut-off by the body of the piston rod and the exhaust valve opened at that end which simultaneously closes the left exhaust valve. At the left the grooves in the piston rod are filled with hot liquid from the tank intake and as the piston is moved to the right by the momentum of the fly wheel the grooves successively commu-

nicate with the cylinder and the small quantity of liquid carried by each groove is immediately vaporized by the heated cylinder. These grooves are so disposed relative to the piston that the liquid feed to the cylinder begins promptly upon the reversal of the direction of piston stroke. The pressure in the cylinder is gradually built-up as the successive grooves discharge and the cooling effect of introducing a larger body of water into the cylinder is obviated. As the piston and its rod travel to the right the valves are automatically shifted as the piston reaches the limit of its travel which also controls, through the piston rod, the feed of hot liquid to the cylinder upon reversal in the direction of movement. The liquid is thus vaporized, condensed and refed to the cylinder so that the degree of heat necessary for vaporization at the cylinder at a high temperature is reduced and the most efficient operation is secured.

While the specific construction of the engine has been shown and described, the invention is not confined thereto, as changes and alterations may be made without departing from the spirit of the invention as recited in the following claims.

What I claim is—

1. In an engine, a cylinder having opposite heads provided with liquid chambers, a piston within the cylinder formed with opposite rods extending through the liquid chambers, a heating chamber surrounding the body of the cylinder for the distance between its heads, means carried by the piston rods at opposite faces of the piston for conveying liquid from the liquid chamber into the cylinder, and means at each head for alternately exhausting the expended vapor from opposite sides of the piston.

2. In an engine, a cylinder having opposite heads provided with liquid chambers, a piston within the cylinder formed with opposite rods extending through the liquid chambers, means for bodily heating the cylinder walls for the distance between its heads, means upon the periphery of the piston rods for collecting liquid in their passage through said chambers and delivering it into the cylinder successively at opposite faces of the piston, means at each head for alternately exhausting the expended vapor from the cylinder, means for condensing the exhausted vapor, and means for refeeding the condensate to the liquid chambers.

3. In an engine, a cylinder having opposite heads, a piston therein provided with a rod extending through said heads, means for bodily heating said cylinder, means controlled by said rod for alternately introducing a liquid at each head of the cylinder, a condensing tank above the cylinder, means for exhausting vapor from the cylinder to the upper portion of said tank alternately

with the liquid introduction, and an intake for the heated liquid at the lower portion of said tank discharging by gravity to the opposite heads of the heated cylinder.

- 5 4. In an engine, a bodily heated cylinder having opposite heads each provided with separate liquid intake and vapor exhaust ports, valves jointly controlling the exhaust ports, a piston within the cylinder, and opposite extending rods from said piston provided with charge conducting pockets disposed adjacent the opposite faces of the piston to alternately feed liquid from the intake to the interior of the cylinder and a solid periphery
10 to close said inlet.
5. In an engine, a cylinder having opposite heads provided with liquid chambers, exterior means for heating the wall of said cylinder, a piston operating within the heated
20 area of the cylinder, opposite rods from said piston formed with grooves disposed to enter one of said chambers at the end of each stroke and a solid periphery to close the outlet from the chamber, and exhaust valves at the cylinder heads controlled by the piston travel to exhaust at alternate sides thereof.

In testimony whereof I affix my signature.
